CLAIM

The ornamental design for a wick bearing lighting device, substantially as shown and described.

DESCRIPTION

FIG. 1 is a perspective view of a wick bearing lighting device, showing my new design;
FIG. 2 is a side elevational view thereof;
FIG. 3 is a top plan view thereof;
FIG. 4 is a bottom plan view thereof;
FIG. 5 is an end elevational view thereof;
FIG. 6 is an elevational view of the opposite end thereof.

*FIG. 1**FIG. 5**FIG. 6**FIG. 2**FIG. 3**FIG. 4*
